UNITED STATES PATENT OFFICE.

JULIUS G. BREITENSTEIN, OF CHICAGO, ILLINOIS, ASSIGNOR TO INDEPENDENT BUTTON & MACHINE COMPANY, OF CHICAGO, ILLINOIS, A CORPORATION.

BUTTON.

No. 899,824.

Specification of Letters Patent. Patented Sept. 29, 1908.

Application filed March 16, 1908. Serial No. 421,528.

To all whom it may concern:

Be it known that I, JULIUS G. BREITENSTEIN, a citizen of the United States, residing at Chicago, in the county of Cook and State 5 of Illinois, have invented new and useful Improvements in Buttons, of which the following is a specification, reference being had to the accompanying drawings, forming a part thereof.

10 The purpose of this invention is to provide a button of improved construction in respect to the means for retaining the cloth tuft.

It consists of the elements and features of construction shown and described as indicated in the claims.

In the drawings:—Figure 1 is a diametric section of a button involving this invention, shown on a greatly enlarged scale, particularly as to the thickness of the parts. Fig. 2 20 is a partial diametric section of the full construction, having certain elements broken away in part in order to disclose features which they would conceal. Fig. 3 is a perspective view of the tuft-retaining disk 25 which characterizes this invention.

A well known and now popular form of button is made with a shell at the back of hard rubber, celluloid, bone, vegetable ivory or like hard material, which is in the form of 30 a shallow cup extending up around the margin of the button and forming the periphery for taking the wear and protecting the cloth face which is encompassed by the marginal wall of this cup-shaped back. The button is 35 substantially complete in formation without this shell, except that for retaining the shell the customary metal collet, which would form the back of the button in the absence of the shell, has its inner circumference provided 40 with projections which extend through the central aperture of the shell for clenching on to the back of the latter to retain it. In forming these clenching projections of the collet, the inner circumference of the latter 45 becomes a folded edge, without any capacity for retaining the tuft which readily slips around such folded edge, so that the tuft in this style of button is liable to be easily pulled out in the absence of some special 50 means for retaining it. The present invention supplies this means, consisting in a tuft-retaining annular disk lodged back of the collet, but being formed with sharply cut edge,

which is preferably also slightly burred at the side toward the cloth disk for forming the 55 tuft which is lodged back of the tuft-retaining annulus so that the tuft is drawn through the aperture which has the sharply cut or burred (edge such as would unavoidably result from making the annular disk in any die 60 and press) instead of being drawn over the smooth folded edge of the collet.

In the drawings, A is the hard rubber, celluloid or bone shell applied at the back of the button and having its flange, A¹, extending 65 up around the periphery for guarding the cloth face.

B is the collet having the clenching teeth or fingers, B¹, extending from its inner circumference and clenched around the inner 70 circumference of the shell, A, on to the back side in the annular rabbet, a, formed for that purpose.

C is the cap and D the cloth face covering the cap and engaged between the flanges of 75 the cap and collet respectively in the customary manner.

E is the cloth tuft disk whose center portion forms the tuft, E¹; F the pasteboard filler back of the disk, E, in the collet, and G is 80 the tuft-retainer,—an annular metal disk lodged in the collet between the same and the cloth disk, E, having its inner circumference burred, as seen at G¹, the bur being turned inward or toward the cloth disk, which, being 85 tucked through the central aperture of the retainer, folds over the burred edge, G¹, in order to protrude through the collet and the shell, A.

I claim:—

1. In a button having a centrally apertured back shell, a collet folded at its inner circumference to form means extending through the aperture of the shell for engaging the same, in combination with a tuft disk having its 95 central portion forming the tuft extending through the central aperture of the collet, and an annular tuft-retaining disk lodged between the tuft disk and the collet having its inner circumference about its central aperture burred on the side toward the tuft disk. 100

2. In a button having a centrally apertured back shell, a collet folded at its inner circumference to form means extending through the aperture of the shell for engaging 105 the same, in combination with a tuft disk

having its central portion forming the tuft
extending through the central aperture of
the collet, and an annular tuft-retaining disk
lodged between the tuft disk and the collet
5 having a sharply cut edge at its inner circum-
ference on the side toward the tuft disk.

In testimony whereof, I have hereunto set

my hand at Chicago, Illinois, this 26th day of
December, A. D. 1907.

JULIUS G. BREITENSTEIN.
